UNITED STATES PATENT OFFICE.

BRADFORD L. AMES, OF BOSTON, MASSACHUSETTS.

SOOT REMOVER FOR WATER-TUBE BOILERS.

Application filed August 19, 1921. Serial No. 493,567.

To all whom it may concern:

Be it known that I, BRADFORD L. AMES, a citizen of the United States, residing at Boston, county of Suffolk, State of Massachusetts, have invented a certain new and useful Improvement in Soot Removers for Water-Tube Boilers, of which the following is a specification, reference being had therein to the accompanying drawings.

10 The invention relates to an improvement in soot removers for water tube boilers. The invention relates to that class of soot removers which comprises a plurality of nozzles through which steam is injected between 15 the tubes of the boiler to remove the soot therefrom. One object of the invention is to provide a unit fully assembled having a plurality of nozzles and which as a complete unit can be connected up with the boiler setting. Another object of the invention is to 20 provide means by which the entire assembly of nozzles may be simultaneously moved to turn them back out of the heat of the furnace when they are not to be operated and 25 can be turned down into the furnace into operative position when desired for use. Another object of the invention is to provide swinging shutters which are automatically closed to protect the nozzles from exposure to the heat when the nozzles are 30 turned back out of operative position, and which are automatically opened when the nozzles are turned into operative position. Other features of the invention will be more 35 particularly set forth hereinafter and disclosed in the claims.

The invention will be fully understood from the following description when taken in connection with the accompanying drawings, and the novel features thereof will be pointed out and clearly defined in the claims at the close of this specification.

In the drawings, Fig. 1 is a plan partly in section of one of the units embodying the 45 invention connected up with a furnace in which vertical boiler tubes are used.

Fig. 2 is a section on line 2—2 of Fig. 1. Fig. 3 is a section on line 3—3 of Fig. 2.

Fig. 4 is a view in elevation partly broken 50 away of a unit embodying the invention, as applied to a furnace having inclined boiler tubes, commonly known as a horizontal water tube boiler.

Fig. 5 is a section on line 5—5 of Fig. 4,

but showing the nozzles in operative position.

Fig. 6 is an enlarged sectional view showing the rotor connection of one of the nozzles with one of the branches of the steam feed tube.

Referring now to the drawings, 1 represents the brick setting of a furnace with which the unit shown in Figure 1 is connected by means of angle iron brackets 2—2. The said unit is provided with a casing having end wall plates 3—3 which are preferably connected with the setting of the furnace by the brackets 2—2, as already described.

The two end walls 3—3 are connected by a front wall plate 4 which extends transversely between the two end plates 3—3.

A main feed tube 5 is provided through which steam is furnished to the nozzles, said feed tube 5 having connected therewith an elbow 6 which together with the main feed tube 5 forms a part of the unit, the elbow 6 being suitably fitted for connection with a main supply tube, not shown, leading from the boiler.

A plurality of branch members 7 are connected with the side of the feed tube 5, extending at right angles thereto, the connection preferably being made by forming each branch 7 with a screw-threaded portion 8 which screws into a threaded aperture in the side of the feed tube 5.

There are provided a plurality of elbows 9 equal to the number of branch members 7, each elbow having a swivel or rotor connection 10 with one of the branch members, and each one of the elbows has a nozzle 11 connected therewith preferably by screw-threaded connection.

The said nozzles are all disposed parallel to each other, and by reason of the swivel connection between the elbows and the branch members, the said nozzles may be rocked in planes parallel to each other.

In the vertical type of construction shown in Figures 1, 2 and 3, the feed tube 5 is disposed horizontally and the elbows 9 being right-angled elbows which are connected with the sides of the branch members, the said nozzles will move in vertical planes parallel with each other.

It is important that all of the nozzles be kept in the same plane with each other and moved all together in parallel planes. In

order to maintain the nozzles in this relation to each other, there are provided two horizontal rods 12-12 which are spaced slightly apart parallel with each other and 5 are mounted in hangers 13-13 which are respectively pivoted at 14 to the two opposite end branch members 7, as shown in Figure 1. Said hangers have each two apertures which form bearings for the said rods 12 10 and are spaced apart from each other so that the two rods embrace the entire series of nozzles, one of said rods being on the upper side and the other on the lower side of each of the nozzles, so that if the said hangers are rocked on their pivots the rods will be carried with the hangers and move the nozzles together, either up or down according to the oscillating or rocking movement 15 of the hangers.

20 Means are provided whereby the said bars may be rocked.

A shaft 15 passes through the front wall of the furnace, its inner end being journaled in a bracket 16 secured to one of the branch feed members 7, preferably to 25 one of the branch members or near the middle of the series, and the outer end of the shaft terminates in a square portion 17 adapted to receive the socket of a handle 30 or wheel to turn the shaft.

Mounted on the shaft is a worm 18 which engages with a worm gear 19. Said gear is also formed with a lug 20 having two 35 apertures through which respectively the two rods 12-12 pass so that the oscillation of said gear will oscillate said rods. By turning the shaft 15 the worm 18 engaging the gear 19 will positively swing the rods 12 in an arc of which the axis of the gear 19 is the center, and thereby cause the 40 oscillation simultaneously and equally of all of the nozzles 11 up or down depending upon the direction in which the shaft 15 is turned. Thus the nozzles 11 may be swung 45 up and down a sufficient arcuate sweep to inject the steam between the boiler tubes for the full length of the tubes.

The several branch numbers and nozzles, 50 feed tube and operating mechanisms described are provided with a casing having a framework 22 to which are attached the side walls 3, 3 previously mentioned, and the front shield 4 for the outer side of the unit, and a plurality of shutters 24 which open to 55 the interior of the furnace and which may be opened to allow the nozzles to be turned down into operative position with relation to the boiler tubes, said nozzles being foldable back into the cabinet or casing between the said shutters and the front shield 4 when the nozzles are intended to be out of use so as to protect the nozzles from injury by being exposed to the heat of the furnace.

60 It is not practical to have the shutters air tight when they are closed, as there must

be room for considerable expansion and for a large amount of dirt. The front shield 4 prevents infiltration of air through the shutters when they are closed and prevents cold air from getting in against the tubes. 70

Means are provided whereby the said shutters will be automatically opened when the nozzles are turned down into operative position, and whereby the said shutters will be automatically closed when the nozzles 75 are turned up into inoperative position within the casing.

Each of said shutters 24 is hinged at top and bottom by the hinge pins 25-25 in the ears 26-26 respectively which are connected with the casing, so that said shutters can swing on said hinges. Each shutter is provided with a chain or other suitable flexible member 27, one end of said chain being fastened at 28 to the shutter and the other end of each of said chains being connected with a floating rod 29 which extends horizontally at some distance above the valve bodies. When the shaft 15 is turned in a direction to cause the nozzles to be turned from the operating position shown in Figures 1 and 2, up into the vertical position in the casing, as shown by dotted lines in Figure 2, said nozzles will engage the rod 29 in their upward movement and carry said rod 29 with them up inside of the casing far enough to cause the shutters to swing closed as shown in Figure 3.

When the shaft 15 is turned in the reverse direction to swing the nozzles down into operative position the ends of the nozzles will strike against the side of the shutters and swing the shutters open, thus allowing the nozzles to drop down into operative position as shown in full lines in Figure 2. 100

The inner walls of the casing to which the shutters are hinged are preferably provided with channel members 30, each of which receives a fire brick 31 to protect the interior wall of the casing from the heat 105 of the furnace.

It is obvious that by simply turning the shaft 15 all of the nozzles will be simultaneously turned down into operative position or turned up out of operative position within the casing according to the direction of turning of the shaft, and also that the shutters will be closed when the nozzles are rocked up in inoperative position and will be opened by the turning down of the nozzles into operative position. 115

The entire apparatus comprising the casing, the branch feed members and nozzles, and the operating shaft together with the worm and gear and the feed tube 5 forms a single unit which may be readily attached to the furnace front in any suitable way. In the form shown in the drawings this means consists of screwing the brackets 125 2-2 to the furnace front and the elbow 130 6

of the feed tube may be readily connected with the steam supply pipe from the boiler (not shown) as already described.

In Figures 4 and 5 there is shown the adaptation of the same principle of construction to a unit for use with a boiler having horizontal tubes or tubes having a slight pitch to the horizontal.

In this construction the boiler tubes 35 which for convenience will be referred to as horizontal tubes, as distinguished from the vertical type already described, are set at a slight angle of pitch and it is important to have the nozzles swing in a plane 15 which is parallel with the boiler tubes so that the nozzles will be always at the same angle of pitch and parallel with the boiler tubes at all times throughout their movement. In this form of construction the feed tube 36 is shown in a vertical position and the nozzles 11^a are disposed one above the other in series and extend between two vertical guide rods 12^a-12^a similar to the horizontal guide rods 12-12 already described, except as to being vertical instead of horizontal. Said guide rods are mounted loosely in hangers 13^a-13^a pivoted to the branch members 7^a and are prevented from working out of position by the collars 48, 20 49 fastened to the rod, one above and one below the lug 20^a on the worm gear 19^a.

An operating shaft 15^a is provided having a worm 18^a engaging with the worm gear 19^a formed with a lug 20^a apertured for 35 engagement with the rods 12^a to swing the nozzles in the manner already described.

A special form of construction for the swivel connection of the elbows 9^a with the branch feed members 7^a is provided to enable the nozzles to swing always in the same plane at the same pitch as the boiler tubes. This form of construction is shown in Figure 6.

The branch 7^a is formed with an aperture 37 through the upper side wall having a flange 38 surrounding said aperture. An annular cap 39 is formed with a flange 40 which is seated upon and secured to the flange 28 of the branch member by bolts 41. The said cap 39 has a neck 42 whose axis is inclined to the axis of the branch member so that the inner face 43 of the annular cap lies in an inclined plane which is at the same angle of inclination as the boiler tubes 35. The elbows 9^a with which the nozzles 11^a are connected have a swivel connection with the cap 39 of the branch member by means of a rotor 44 which is screwed into the elbow, said rotor having a smooth shank portion 45 which turns readily in the bore of the cap 39. Said rotor has a head 46 having a flat smooth inner surface 47 which is seated upon the inner face 43 of the cap 39, so that the said rotor can

turn easily in the bearing formed by said cap 39. Thus the axis of the nozzles always remains parallel to the pitch of the tubes and the nozzles will swing in planes which are of the same pitch as the tubes 35 of the boiler.

The shutters 24^a are hung on horizontal pintles 25^a so that the said shutters swing up and down. When the nozzles are swung out of their casing into operative position, they will swing the shutters up on their hinges, as shown in Figure 5, and when the nozzles are turned back into their enclosing case, the said shutters will simply close by gravity; therefore, it is not necessary in this type of boiler to have the floating bar 29 so such as previously described for the vertical type of boiler.

The threads of the worm gear preferably have about ten to one reduction from the worm, so that when the worm shaft is 85 turned the nozzles will move very slowly and give more chance for the steam from the nozzles to play upon the tubes and to reach the tubes at the farthest point away which would be less likely to take place if 90 the worm gear turned at the same speed as the shaft.

What I claim is:—

1. A soot blower for a boiler comprising a steam supply pipe, a plurality of nozzles 95 parallel with each other, projecting laterally from said pipe, a swivel connection between each nozzle and said supply pipe, guides having an elongated space between them through which said nozzles loosely 100 pass, and means for oscillating said guides bodily in an arcuate path whereby said guides cause said nozzles to simultaneously sweep through arcuate paths in parallel planes. 105

2. A soot blower for boilers comprising a steam supply pipe, a plurality of nozzles projecting laterally from said supply pipe parallel to each other, a swivel connection between one end of each nozzle and the supply pipe, a pair of guides between which said nozzles loosely pass, and means for 110 swinging said guides bodily in an arcuate path, said guides in their movement engaging said nozzles and thereby causing all of said nozzles to simultaneously sweep through arcuate paths in parallel planes. 115

3. A soot blower for boilers comprising a steam supply pipe, a plurality of nozzles projecting laterally from said supply pipe parallel to each other, a swivel connection between one end of each nozzle and the supply pipe, guides between which said nozzles loosely pass, a rocker shaft, and gear connection between said rocker shaft and said guides, whereby the rocking of said shaft causes the said guides to bodily swing in an arcuate path and thereby to oscillate the said 120 125

nozzles so that their outer ends sweep through arcuate paths in planes parallel with each other.

4. A soot blower for boilers comprising a steam supply pipe, a plurality of branches connected with ports in the side of the said supply pipe, a plurality of nozzles, one for each branch, parallel with each other and each having a swivel connection at one end 10 with one of said branches, guides having an elongated space between them through which said nozzles loosely pass, and means for oscillating said guides bodily in an arcuate path, whereby all the said nozzles are simultaneously caused to sweep through arcuate paths in parallel planes.

5. A soot blower for boilers comprising a steam supply pipe, a plurality of branches connected with ports in the side of the said supply pipe, a plurality of nozzles one for each branch parallel with each other and each having a swivel connection at one end 20 with one of said branches, guides having an elongated space between them through which said nozzles loosely pass, a rocker shaft, and gear connection between said rocker shaft and said guides, whereby the rocking of said shaft causes the said guides to bodily swing in an arcuate path and thereby to move the 30 said nozzles so that their outer ends sweep through arcuate paths in planes parallel with each other.

6. A soot blower for boilers comprising a steam supply pipe, a plurality of branch members connected with ports in the sides of said supply pipe, a plurality of nozzles one for each branch parallel with each other and each having a swivel connection at one end 35 with one of said branch members, two parallel guide rods having a space between them through which said nozzles pass, a plurality of hangers each pivotally connected at one end with one of said branch members, the swinging ends of said hangers 40 having apertures through which said guide rods pass, a rocker shaft having a worm mounted thereon, a gear engaging with said worm and having a lug through which said guide rods pass, whereby the rocking of 45 said shaft oscillates said guides and thereby simultaneously oscillates bodily all of said nozzles causing them to sweep through arcuate paths in parallel planes.

7. A soot blower for boilers comprising a steam supply pipe, a plurality of branch members connected with ports in the side of the said supply pipe, a plurality of nozzles one for each branch parallel with each other and each having a swivel connection at one 50 end with one of said branches, guides having an elongated space between them through which said nozzles loosely pass, a rocker shaft, gear connection between said rocker shaft and said guides, whereby the 55 rocking of said shaft causes the said guides

to bodily swing in an arcuate path and thereby to oscillate the said nozzles so that their outer ends sweep through arcuate paths in planes parallel with each other, a casing in which said steam supply pipe is 70 mounted and which supports all of the elements previously set forth herein, thereby forming a unitary structure, and means for attaching the said unitary structure to the wall of a furnace having boiler tubes in such 75 manner that the said nozzles may be oscillated to sweep between the boiler tubes.

8. A soot blower for boilers comprising a steam supply pipe, a plurality of branch members connected with ports in the side of the said supply pipe, a plurality of nozzles one for each branch member parallel with each other and each having a swivel connection at one end with one of said branches, guides having an elongated space between them through which said nozzles loosely pass, a rocker shaft, gear connection between said rocker shaft and said guides, whereby the rocking of said shaft causes the said guides to bodily swing in an arcuate path and thereby to oscillate the said nozzles so that their outer ends sweep through arcuate paths in planes parallel with each other, a casing in which said steam supply pipe is 80 mounted and which supports all of the elements previously set forth herein, thereby forming a unitary structure, and means for attaching the said unitary structure to the wall of a furnace having boiler tubes in such 85 manner that the said nozzles may be oscillated to sweep between the boiler tubes.

9. A soot blower for boilers comprising a steam supply pipe, a plurality of branch members connected with ports in the side of the said supply pipe, a plurality of nozzles one for each branch member parallel with each other and each having a swivel connection at one end with one of said branches, guides having an elongated space between them through which said nozzles loosely pass, a rocker shaft, gear connection between said rocker shaft and said guides, whereby the rocking of said shaft causes the said guides to bodily swing in an arcuate path and thereby to oscillate the said nozzles so that their outer ends sweep through arcuate paths in planes parallel with each other, a casing in which said steam supply pipe is 90 mounted and which supports all of the elements previously set forth herein, thereby forming a unitary structure, and means for attaching the said unitary structure to the wall of a furnace having boiler tubes in such 95 manner that the said nozzles may be oscillated to sweep between the boiler tubes.

10. A soot blower for boilers comprising a steam supply pipe, a plurality of branch members connected with ports in the side of the said supply pipe, a plurality of nozzles one for each branch member parallel with each other and each having a swivel connection at one end with one of said branches, guides having an elongated space between them through which said nozzles loosely pass, a rocker shaft, gear connection between said rocker shaft and said guides, whereby the rocking of said shaft causes the said guides to bodily swing in an arcuate path and thereby to oscillate the said nozzles so that their outer ends sweep through arcuate paths in planes parallel with each other, a casing in which said steam supply pipe is 100 mounted and which supports all of the elements previously set forth herein, thereby forming a unitary structure, and means for attaching the said unitary structure to the wall of a furnace having boiler tubes in such 105 manner that the said nozzles may be oscillated to sweep between the boiler tubes.

110

115

125

120

130

for attaching the said unitary structure to the wall of a furnace of a water tube boiler in such manner that the said nozzles may be oscillated to sweep between the boiler 5 tubes, and which may be turned back into the casing by rotating the rocker shaft in the reverse direction, said casing being provided with shutters which are normally closed when the nozzles are turned back 10 into the casing and which are engaged by the nozzles to automatically open the shut-

ters when the nozzles are rocked down into operative position with relation to the boiler tubes, and a swinging bar having flexible connections with all of said shutters, said 15 bar being suspended in position where it will be engaged by said nozzles when said nozzles are swung back into the covering and thereby close the shutters.

In testimony whereof I affix my signature. 20

BRADFORD L. AMES.
